WEB REGISTERING MECHANISM

James Degnan, Corona, N. Y., assignor to Speedry
Gravure Corporation, New York, N. Y., a cor-
poration of New York

Application March 4, 1937, Serial No. 128,888

15 Claims. (Cl. 101—181)

The present invention relates to devices for maintaining the register of a printed web upon which a plurality of printing operations are to be effected. Where a continuous web is subjected to more than one printing operation, as, for example, where the web is to receive multi-color printing, the importance of maintaining accurate registration of the web with respect to the printing surface of the respective printing cylinders will be readily apparent. Inaccuracies in such registration result in imperfect printing, and registration, therefore, becomes a highly important factor in multi-impression printing operations.

In existing multi-impression printing operations adjustment of the web for registration is effected manually, samples of the printed product being examined and manual adjustments made in accordance with the conditions of operation evidenced by such samples.

The objections and disadvantages of such operations will be apparent and an object of the present invention is to provide a mechanism by means of which faulty registration will be detected in its inception.

A further object of the invention is to provide a mechanism by means of which accurate registration of the web may be maintained at all times.

A further object of the invention is to provide a device of the above character wherein any tendency of the web toward faulty registration will be corrected automatically and in such fashion as to maintain accurate registration of the web at all times.

Further objects of the invention will be apparent as it is described in greater detail in connection with the accompanying drawings, wherefore:

Figure 1 is a diagrammatic view of a printing operation upon a continuous web, such operation consisting of superimposing one impression upon another, wherein the need for accurate registration exists.

Figure 2 is a schematic diagram showing the electrical circuits by means of which the mechanism of the present invention operates, this view illustrating the condition of the mechanism when proper registry of the web with a printing cylinder exists.

Figure 3 is a view similar to Figure 2 showing the mechanism of the present invention operating when the web is lagging, that is, when a portion of the web reaches the cylinder too late, in point of time, to have the impression made

upon it in such fashion as to register correctly with the previous impression.

Figure 4 is a view similar to Figure 2 showing the condition existing when the web is leading, that is, when the web reaches the printing surface too soon to have accurate registration of the printing surface with the prior impressions.

Referring to the above drawings, Figure 1 illustrates the pertinent portions of a printing press upon which the present invention may be installed. The web is provided in the form of a supply roll 10, suitable unwinding mechanism being provided to feed the web 11 over an idler roll 12 and to a printing cylinder 13. An impression roller 14 maintains the web against the printing cylinder 13 and thereby causes the desired impression to be made upon one side of the web. From this printing unit, the web passes over a roll 15 and to an idler roll 16, from which the web passes to a second printing unit consisting of a printing cylinder 17 and an impression cylinder 18. It will be seen that this printing unit prints upon the other side of the web and the web then passes to a web tensioning roll 19, from which it is carried to the third printing unit consisting of printing cylinder 20 and impression cylinder 21. This third printing unit makes an impression upon the web which must register accurately with the impression made by the printing cylinder 17. In order that this impression may register accurately with the impression made by cylinder 17, mechanism is provided, in accordance with the present invention, this mechanism now being described.

The printing cylinders are driven by a common drive shaft 22, by means of a motor 23 and suitable driving connections such as worm gears 24. Upon shaft 22 there is provided a cam 25 which operates a circuit interrupter 26 in a manner to be described hereinafter. The shaft 22 is also provided with a directional switch 27, this switch being formed as a drum and provided with a continuous contact ring 28, a contact segment 29 which extends through almost one-half of the periphery of the switch drum 27, and a contact segment 30 which likewise extends throughout almost one-half of the periphery of the switch drum 27 but upon the other side thereof from the segment 29. Contact finger 31 engages contact ring 28 while contact finger 32 engages segment 29 and contact finger 33 engages segment 30. The construction of the switch 27 and segments 29 and 30 is such that at no time will the contact fingers 32 and 33

both be engaging the respective contact segments 29 and 30 at the same time.

In operation, the printing cylinders are engraved with a suitable indexing indicia at a portion thereof out of the printing zone. For example, cylinder 17, preferably at one of the margins thereof, is provided with engraving which will make a suitable mark upon the web at the time of the impression thereof. In order 10 that the registration of this portion of the web with each succeeding cylinder may be correct, this mark must reach the point of impression of each of the succeeding cylinders at the time when the corresponding portions of each of such 15 succeeding cylinders is to make the impression which is to be superimposed upon this portion of the web. Obviously, the specific character of this indicia is of no particular importance except that it must not have too great a dimension 20 in the direction of travel of the web to render the mechanism not sufficiently sensitive.

Suitably positioned along the path of travel of the indexing indicia is a photoelectric cell 34 for each of the successive printing cylinders with 25 which the web is to register. Only one such cell has been shown herein and the circuit for this cell is illustrated in each of the diagrams shown in Figures 2, 3 and 4. Such circuit consists of a wire 35 which connects the cell to the grid of a 30 thyratron tube 36 of the type known in the trade as type 112A. The other terminal of the cell 34 is connected to the filament of the tube 36 by a wire 37 and through resistances 38 and 39. In a typical tube circuit, resistance 38 is of 6000 ohms 35 while resistance 39 is of 600 ohms.

The filament circuit of tube 36 includes wires 40, 41 and 42, a resistance 43 being connected in the wire 40 and a lamp 44 in the wire 42. In the typical circuit above referred to, the resistance 43 is of 100 ohms and the lamp 44 is of 25-watt 110-volt rating. The terminals of wires 40 and 41 are connected to a 110-volt source of current.

A resistance 45 is connected between wires 37 45 and 41 by means of a wire 46 in the typical circuit above referred to, resistance 45 being of 4000 ohms.

The plate circuit of the tube 36 includes wires 47 and 48, wire 48 being connected to wire 42 and 50 lamp 44. A condenser 49 is connected across the plate circuit by means of a wire 50, the condenser having a rating of one microfarad in the typical circuit above referred to.

A relay 51 is connected in the plate circuit, this 55 relay having a contactor 52 which is adapted to engage terminals 53 and 54. Terminal 53 is connected to a suitable power source by means of a wire 55 while terminal 54 is connected to the circuit interruptor 26 by means of a wire 56. The 60 interruptor 26 is adapted to engage a stationary contact 57 which is connected to the contact finger 31. The interruptor 26 is operated by means of a cam 25 which, as above described, is mounted on or synchronized with the rotation of 65 the drive shaft 22.

The directional switch 27, as previously described, is mounted on the drive shaft 22 or synchronized with the rotation thereof.

Contact finger 32 is connected to a wire 58 70 which is connected in turn to lamp 60 and to wire 59 which is connected to the source of power to which wire 55 is connected. In the circuit formed by the wire 59, a lamp or other suitable indicator is connected in order to give an indication 75 in the event of a lagging condition of the

web. Contact finger 33 is connected to the wire 58 by means of a wire 61 which also includes a lamp or other indicator 62 to give an indication of the existence of a leading web.

In order that the web tensioning roll 18 may 5 be adjusted to compensate for leading or lagging conditions of the web, a reversible motor 63 is suitably connected thereto. The specific connection and operation of the web tensioning roll by the motor 63 forms no part of the present invention and, therefore, is only illustrated schematically in the drawings. In the construction illustrated, the motor 63 is a 3-phase reversing motor and may be controlled by means of any suitable reversing mechanism operated by relays 10 responsive to current flowing through the respective wires 58 and 61. In order that this may be illustrated more fully, two interlocked relays 64 and 65 are illustrated, relay 64 being adapted to close contact members 66, 67 and 68 while 15 relay 65 is adapted to close the contact members 69, 70 and 71. An armature 72 is connected to the contacts 66, 67 and 68 and is responsive to relay coil 64 while an armature 73 similarly connected to contacts 69, 70 and 71 is responsive to 20 relay 65. These armatures may be suitably interlocked in order to prevent a condition in which all of the contacts are in a closed position. For this purpose, and in the diagrammatic illustration shown in the drawings, the 25 armatures 72 and 73 are mounted upon a common shaft. Relay coil 64 is connected across lamp 68 by means of wires 74 and 75, while relay coil 65 is connected across lamp 62 by 30 means of wires 76 and 77. It will thus be seen 35 that when the circuit formed by the wire 58 is energized, the contacts 66, 67 and 68 will be closed to connect a motor M with a 3-phase power supply indicated by the terminals L¹ and L² and L³. These terminals are connected to t₁ and t₂; t₃ and t₄; and t₅ and t₆, respectively.

The motor terminals T₁, T₂, T₃ are connected 40 respectively to terminals t₁, t₂; t₂, t₃; and t₃, t₁. It will thus be seen that the motor M will be operated in one direction when the wire 58 is energized and in the other direction when the wire 61 is energized. In this fashion, the tensioning of the web is effectively controlled by the motor.

Figure 2 illustrates the case where the web 11 45 is in accurate registry with the printing surfaces of the respective printing cylinders. The indexing indicia is shown directly in the path of the photo-electric cell 34 so that an instantaneous current impulse is transmitted to the grid of the thyratron tube 36, thereby closing the contacts 53 and 54 of the relay 51. At this instant, however, the interruptor 26 has opened the circuit, so that neither of the signal lamps 60 and 62 is 50 energized.

A lagging web is illustrated in Figure 3, where 55 the actual position of the indexing indicia is indicated by the solidly drawn spot on the web 11, and the position of the indicia for accurate registry is indicated by the spot shown in dotted lines. In this case, contact finger 26 is in engagement with contact 57 at the instant when the indexing indicia passes before the photocell 44. The subsequent closure of the relay 51 therefore, supplies voltage to the lamp 62 through 60 the segment 58, and at the same time energizes the relay 65, thereby energizing the motor 14 and increasing the tension in the web 11.

In Figure 4 is shown the case where the web 65 is leading. Here, at the instant when the in- 70

dexing indicia passes before the photocell 34, the cam 25 has not quite reached the position for interrupting the circuit, so that the closure of the relay 51 supplies voltage through the contact 5 segment 29 to the lamp 60 and also to the relay 64. The operation of relay 64 reverses the phase rotation of the voltage supplied to the motor 14 so that it rotates in the reverse direction to decrease the tension in the web 11.

10 The foregoing construction is sensitive to varying conditions of registration of the web insofar as the web tends to lead or lag, and these conditions are corrected in their incipiency. The device may be combined with a controlling motor 15 for which automatically corrects the registration, or it may simply be used as an indicator, the press screw making manual corrections of registration in response to indicated faults.

While the invention has been described with 20 reference to the construction shown in the accompanying drawings, it is not to be limited save as defined in the appended claims.

I claim:

1. Web register mechanism for printing presses 25 having a plurality of printing cylinders comprising means responsive to preconditioned portions of the web, a plurality of electro responsive means, electric circuits for each of the last named means, rotatable means in timed relation with 30 the printing cylinders for making a connection to the circuits alternately and at regular intervals, and means actuated by the means responsive to the preconditioned portions of the web for controlling the circuits.

35 2. Web register mechanism for printing presses having a plurality of printing cylinders comprising means responsive to preconditioned portions of the web, a plurality of electro responsive means, electric circuits for each of the last 40 named means, rotatable means in timed relation with the printing cylinders for making a connection to the circuits alternately and at regular intervals; an interrupter in the circuit in timed relation with the printing cylinders, and 45 means actuated by the means responsive to the preconditioned portions of the web for controlling the circuits.

3. Web register mechanism for printing presses 50 having a plurality of printing cylinders comprising means responsive to preconditioned portions of the web, a pair of indicating means, electric circuits for each of the last named means, rotatable means in timed relation with the printing cylinders for making a connection 55 to the circuits alternately and at regular intervals, and means actuated by the means responsive to the preconditioned portions of the web for controlling the circuits.

4. Web register mechanism for printing presses 60 having a plurality of printing cylinders comprising means responsive to preconditioned portions of the web, means to vary the motion of the web with respect to a printing cylinder, a plurality of electro responsive means, electric 65 circuits for each of the last named means, means to actuate the means to vary the motion of the web by the electro responsive means, rotatable means in timed relation with the printing cylinders for making a connection to the circuits 70 alternately and at regular intervals, and means actuated by the means responsive to the preconditioned portions of the web for controlling the circuits.

75 5. Web register mechanism for printing presses having cylinder driving means and a plurality

of printing cylinders for superimposing upon an impression of a first cylinder the impression of a second cylinder, wherein the first cylinder applies indexing indicia on the web, comprising means responsive to the indexing indicia, electro responsive means, circuits to actuate the last named means by the means responsive to the indexing indicia, an interrupter in one of the circuits for breaking the said circuit at regular intervals and driven by the cylinder drive means, 10 and a directional switch in one of the circuits and driven in timed relation with the cylinder driving means.

6. Web register mechanism for printing presses having cylinder driving means and a plurality 15 of printing cylinders for superimposing upon an impression of a first cylinder the impression of a second cylinder, wherein the first cylinder applies indexing indicia on the web, comprising means responsive to the indexing indicia, electro 20 responsive means, circuits to actuate the last named means by the means responsive to the indexing indicia, an interrupter in one of the circuits and driven by the cylinder drive means, and a rotatable switch driven in timed relation 25 with the cylinder drive means and having a continuous contact ring and alternate contact segments connected to the circuit of the electro responsive means.

7. Web register mechanism for printing presses 30 having cylinder driving means and a plurality of printing cylinders for superimposing upon an impression of a first cylinder the impression of a second cylinder, wherein the first cylinder applies indexing indicia on the web, comprising 35 means responsive to the indexing indicia, two electro responsive means, circuits to actuate the last named means by the means responsive to the indexing indicia, an interrupter in one of the circuits driven by the cylinder drive means, 40 and a rotatable switch driven in timed relation with the cylinder drive means having a continuous contact ring and alternate contact segments connected to the respective two electro responsive means.

45 8. Web register mechanism for printing presses having cylinder driving means and a plurality of printing cylinders for superimposing upon an impression of a first cylinder the impression of a second cylinder, wherein the first cylinder applies indexing indicia on the web, comprising 50 means responsive to the indexing indicia, two electro responsive means, circuits to actuate the last named means by the means responsive to the indexing indicia, an interrupter in one of the circuits driven by the cylinder drive means, and a rotatable switch driven in timed relation 55 with the cylinder drive means having a continuous contact ring and alternate contact segments connected to the respective two electro responsive means, and means actuated by the two electro responsive means to cause the web to be advanced or retarded in relation to a printing cylinder.

60 9. Web register mechanism for printing presses 65 having cylinder driving means and a plurality of printing cylinders for superimposing upon an impression of a first cylinder the impression of a second cylinder, wherein the first cylinder applies indexing indicia on the web, comprising 70 means responsive to the indexing indicia, a first circuit including the said responsive means, a relay in the first circuit, an indicia circuit, means to actuate the indicia circuit by the relay, and means driven in timed relation with the cylinder 75

der driving means to control the indicia circuit.

10. Web register mechanism for printing presses having cylinder driving means and a plurality of printing cylinders for superimposing upon an impression of a first cylinder the impression of a second cylinder, wherein the first cylinder applies indexing indicia on the web, comprising means responsive to the indexing indicia, a first circuit including the said responsive means, a relay in the first circuit, an indicia circuit, means to actuate the indicia circuit by the relay, means actuated by the indicia circuit to cause the web to be advanced or retarded in relation to a printing cylinder, and means driven in timed relation with the cylinder driving means to control the indicia circuit.

11. Web register mechanism for printing presses having cylinder driving means and a plurality of printing cylinders for superimposing upon an impression of a first cylinder the impression of a second cylinder, wherein the first cylinder applies indexing indicia on the web, comprising means responsive to the indexing indicia, a first circuit including the said responsive means, a relay in the first circuit, means to cause the web to be advanced or retarded in relation to a printing cylinder, means to actuate the last named means by the relay, and means driven in timed relation with the cylinder driving means to control the indicia circuit.

12. Web register mechanism for printing presses having cylinder driving means and a plurality of printing cylinders for superimposing upon an impression of a first cylinder the impression of a second cylinder, wherein the first cylinder applies indexing indicia on the web, comprising means responsive to the indexing indicia, a first circuit including the said responsive means, a relay in the first circuit, a second circuit including the relay contacts, an interrupter in the second circuit driven in timed relation with the cylinder driving means, a rotary switch driven in timed relation with the cylinder driving means, a contact ring on the rotary switch connected in the second circuit, alternately spaced contact segments on the rotary switch connected to the contact ring, and electroresponsive means connected to the segments and in the second circuit.

13. Web register mechanism for printing presses having cylinder driving means and a plurality of printing cylinders for superimposing upon an impression of a first cylinder the impression of a second cylinder, wherein the first cylinder applies indexing indicia on the web, comprising means responsive to the indexing indicia, a first circuit including the said responsive means,

a relay in the first circuit, a second circuit including the relay contacts, an interrupter in the second circuit driven in timed relation with the cylinder driving means, a rotary switch driven in timed relation with the cylinder driving means, a contact ring on the rotary switch connected in the second circuit, alternately spaced contact segments on the rotary switch connected to the contact ring, electroresponsive means connected to the segments and in the second circuit, a third circuit, means in the third circuit to control the web, and means to control the third circuit by the last named electroresponsive means.

14. Web register mechanism for printing presses having cylinder driving means and a plurality of printing cylinders for superimposing upon an impression of a first cylinder the impression of a second cylinder, wherein the first cylinder applies indexing indicia on the web, comprising means responsive to the indexing indicia, a first circuit including the said responsive means, a relay in the first circuit, a second circuit including the relay contacts, an interrupter in the second circuit driven in timed relation with the cylinder driving means, a rotary switch driven in timed relation with the cylinder driving means, a contact ring on the rotary switch connected in the second circuit, alternately spaced contact segments on the rotary switch connected to the contact ring, electroresponsive means connected to the segments and in the second circuit, a third circuit, a reversing motor in the third circuit and adapted to control the web, and relays connected across each of the electroresponsive means to control the third circuit.

15. Web register mechanism for printing presses having cylinder driving means and a plurality of printing cylinders for superimposing upon an impression of a first cylinder the impression of a second cylinder, wherein the first cylinder applies indexing indicia on the web, comprising means responsive to the indexing indicia, a first circuit including the said responsive means, a relay in the first circuit, a second circuit including the relay contacts, an interrupter in the second circuit driven in timed relation with the cylinder driving means, a rotary switch driven in timed relation with the cylinder driving means, a contact ring on the rotary switch connected in the second circuit, alternately spaced contact segments on the rotary switch connected to the contact ring, a third circuit, means in the third circuit to control the web, and electroresponsive means connected to the segments and in the second circuit to control the third circuit.

JAMES DEGNAN.
